UNITED STATES PATENT OFFICE

2,438,321

FOOTWEAR

Roy Maling, Chestnut Hill, Mass.

Application September 19, 1945, Serial No. 617,222

3 Claims. (Cl. 36—11)

1

This invention relates to improvements in foot-wear.

More particularly it provides an improved moccasin type shoe and slipper structure.

It is an object of the invention to provide moccasin types of footwear having provision therein for supporting the arch of the wearer's foot.

Another object is to provide a moccasin type of footwear wherein a cushioning platform intervenes between the tread sheet and the foot of the wearer.

It is, moreover, my purpose and object generally to improve upon prior shoe-making procedures and prior footwear structures, especially as applied to moccasin types of shoes and slippers.

In the accompanying drawing:

Figure 1 is a perspective view of a pre-stitched upper lining and sock-lining;

Figure 2 is a perspective view of a platform and heel unit;

Figure 3 is a perspective of a moccasin base sheet pre-formed for reception therein of the elements shown in Figures 1 and 2;

Figure 4 is a perspective of the forepart top element which is laced in place in Figure 5; and

Figure 5 is a side elevation of an assembled shoe embodying features of the invention, with portions broken away to show the interior structure.

Referring to the drawing, Fig. 1 illustrates a lining 10 and a sock-lining 12 stitched together at 14 all around the elements. The lining and sock-lining may be of any suitable material but I prefer to employ leather in order to provide serviceable and attractive surfaces which are to be exposed interiorly of the shoe.

In Fig. 3 there is shown a pre-formed moccasin base sheet 16 which is a single sheet, preferably of flexible and relatively heavy leather stock, so that its portion 18 which constitutes the tread surface will be durably strong and wear-resisting. A suitable blank is stamped out or otherwise cut from a larger sheet, and the blank may be formed into the general shape as shown in Fig. 3, being stitched at 20 at the rear and at 22, 24 at the forepart, so that an open-top receptacle is provided having integral bottom and side walls. The sheet 16 may be shaped and stitched on a suitable form, if desired, although a properly cut blank easily may be shaped and stitched with sufficient accuracy without the aid of a form. If the forepart top sheet 26 of Fig. 4 is to be laced in place, as shown in Fig. 5, it will be provided

2

with the lacing holes 28, and the lacing holes 30 preferably will be formed in the sheet 16 when it is being blanked out or otherwise cut.

According to the invention, an arch supporting unit is provided within the pre-formed base sheet 16. As herein represented, a platform and heel unit 32 is provided as best seen in Fig. 2. This may be composite of a full length platform element 36, of felt or other suitable resilient material, and a heel lift element 38 which may be of wood or other rigid material. If desired the heel lift may be of resilient material with any known variety of shank stiffener within the composite unit structure.

15 With the pre-formed elements of Figs. 1-4 ready, the shoe of Fig. 5 may be assembled by placing the platform and heel unit 32 in the pre-formed unitary sheet receptacle 16, and then lowering the pre-stitched lining and sock-lining unit 20 into the receptacle 16 above the unit 32. Then, while holding the elements in assembled relation, the top edges of the sheet receptacle 16 and the top edges of the lining 10 are stitched together at 40 all around the shoe. Preferably, the lining, 25 at its rear top edge, will have flap portions 42, 44 for being turned over the raw edge of the sheet 16 as a binding, as shown at 46 in Fig. 5.

A more stable product will be attained if, prior to assembly of the pre-formed elements, the surfaces which are to rest together are coated with adhesive to prevent relative slip of the associated elements in the finished shoe.

If desired, a form or last plate may be inserted 35 in the shoe to press the base elements together while the sheet 16 is being drawn tight and stitched at 40 to the lining although the pre-forming of the elements enables assembly without any form.

40 After stitching at 40, the top sheet 26 may be laid in place and laced to sheet 16 at the forepart, as indicated at 48 in Fig. 5. It should be understood, however, that the sheet 26 may be stitched in place, if desired.

45 I claim as my invention:

1. An article of footwear, comprising an upper lining and a sock-lining stitched together all around the sock-lining, a platform and heel unit underlying the sock-lining, and a unitary tread sheet extending integrally under the platform and heel unit and integrally upward all around the article and over the upper lining and secured to the top edge of the upper lining all around the article, said sheet having smooth continuity of 50 extent from the plane of the tread surface of

the article to the top edge of the article all around the article.

2. An article of footwear, comprising an upper lining and a sock-lining stitched together all around the sock-lining, a unitary sheet having a portion extending integrally over the full tread area of the article and integral portions extending upward all around the tread portion, said upward extending portions of the unitary integral sheet covering the full area of the upper lining all around the article and being secured to the top marginal portion of the lining all around the article, a foot-supporting member intervening between the sock-lining and the tread portion of said unitary integral sheet, and means at the forepart of the article extending across from the top edge of the lining at one side of the article to the top edge of the lining at the other side, said unitary sheet having smooth continuity of extent from the plane of the tread surface of the article to the top edge of the article all around the article.

3. A moccasin type shoe, comprising a unitary integral sheet of flexible material extending as an upper downward from the top edge of the shoe all around the shoe and extending integrally over the full tread area of the shoe as a tread, an upper lining stitched to the unitary integral

sheet all around the top edge of the shoe, a sock-lining stitched to the lower edge of the lining all around the shoe, a foot-supporting unit intervening between the sock-lining the tread portion of the unitary integral sheet, and means extending across the forepart of the shoe from the opposite top edges of the upper, said unitary integral sheet having smooth continuity of extent from the top edge of the shoe to the plane of the tread surface all around the shoe.

ROY MALING.
